C. D. FAHL.
GREASER FOR TROUSERS.
APPLICATION FILED JUNE 25, 1908.

902,808.

Patented Nov. 3, 1908.

UNITED STATES PATENT OFFICE.

CLEMENT D. FAHL, OF PHILADELPHIA, PENNSYLVANIA.

CREASER FOR TROUSERS.

No. 902,808.

Specification of Letters Patent.

Patented Nov. 3, 1908.

Application filed June 25, 1908. Serial No. 440,229.

To all whom it may concern:

Be it known that I, CLEMENT D. FAHL, a citizen of the United States, residing at Philadelphia, in the county of Philadelphia and State of Pennsylvania, have invented 5 certain new and useful Improvements in Creasers for Trousers, of which the following is a specification.

My invention relates to certain new and 10 useful improvements in creasers for trousers, the object being to provide a device which will crease and stretch the trousers, so as to form a crease in the front and back portions of the legs, and remove the fullness at the 15 knees.

Another object is to provide a device which is simple and cheap in construction and which can be readily clamped over the 20 legs of a pair of trousers.

These objects are attained by the novel 25 arrangement and construction of parts hereinafter fully described and shown in the accompanying drawings, in which:

Figure 1, is a perspective view of my improved creaser. Fig. 2, is a section taken on line 2—2 of Fig. 1 showing a pair of trousers arranged therein, and Fig. 3, is a section taken on line 3—3 of Fig. 1 showing a portion of the trouser leg between the members.

In the drawings A designates two opposed 30 longitudinally extending base strips or bars preferably made of wood of a length greater than the length of a pair of trousers, and adapted to contact with one face of a trouser- 35 leg. At their upper and lower ends they are spaced apart by adjustable spacing bars so that one end of the stretcher may be wider than the other to provide for the widening of the trouser leg as it nears the hip, 40 and also to provide for a lateral adjustment of the two bars in order to stretch the trousers as will be hereafter described.

While I do not wish to be limited to any 45 particular spacing means, I prefer to use at each end of the stretcher the construction shown in the drawings which consists of two flat bars C and D contacting and moving on each other, one of said bars being attached to each one of said longitudinal pieces A. 50 One of the bars is slotted as at e, the other has a bolt d passing through the slot provided with a clamp nut d' thereon. The bar C is provided at its end with an up-turned stop and the bar D with upwardly turned 55 lateral wings d'' adapted to engage with the edges of the bar C, thus preventing the bars

from having any pivotal motion on each other.

Hinged upon the outer edges of the bars or strips A are the flat bars or strips B, 60 65 their ends being preferably attached on either side of the middle of the strips, so as to give a firm support to the middle portion thereof. The bars or strips B are shorter than the strips A and are beveled at their ends for engagement with the beveled 70 end faces of a pair of angular, pivotally mounted, clamping buttons E, E, one at the top and the other at the bottom of each of the strips A. The pivots are formed by 75 bolts or screws e passing through the button and provided with nuts or heads on their under side.

As shown in Figs. 1 and 3, the inner face of the projecting portions e' of the buttons 80 E are beveled laterally from the inside outwardly and upwardly, while each end of the strips B on their outer faces is beveled inwardly and towards the end. It will thus be seen that as the buttons are turned inwardly 85 to the position shown in the leg on the left hand side of Fig. 1, they will have a wedging action against the strips B forcing them tightly against the outer faces of the strips A, and holding them there.

In order to make a good contact and prevent wear of the wood, I prefer to provide 90 wearing plates F on the beveled face of the strips B against which the buttons shall contact.

In order to make the lateral adjustment 95 of the strips easy, I provide the springs G which connect one strip A with the other, and which, when the clamp nuts d' are unloosed, act to draw the bars or strips A towards each other.

The inside faces of the strips A and of the hinged strips B are preferably lined with 100 felt F, and strips of cardboard or other fabric H' are provided to be placed on either side of the trousers when in the press.

The operation of my device is as follows: 105 The hinged clamping strips B are turned outwardly and the strips A are adjusted from each other to suit the size of the trousers to be pressed. This is accomplished by adjusting the bars C, D, upon each other and clamping them in their adjusted position. One trouser leg is then laid on the strips A and B, so as to bring the front and 110 back portion of the trouser leg into correct position on the strips. A strip of cardboard

H' is then laid over the front and back portion of the leg and the other trouser leg brought down and laid upon the strip of cardboard.

5 The clamping strips B are then folded inward and down upon the fabric of the trousers at the crease and the buttons are turned so that they engage the beveled faces of the clamping strips.

10 It will be seen that by forcibly turning the buttons, the hinged strips will be forced downward and clamped against the inner faces of the strips A so tightly as to form a crease. After the trousers have been placed 15 in position in this manner the strips A are forced apart laterally and locked so as to stretch the legs laterally.

Having thus described my invention what I claim as new and desire to secure by Letters Patent is:

1. A trousers creaser having two opposed longitudinally extending base strips adjustably spaced apart so as to engage the edges of a trouser leg, a clamping strip of the same 25 width as said base strip hinged to each of said base strips, shorter than the same and adapted to fold over upon the same, and clamping buttons pivoted on the upper and

lower ends of each of said base strips above and below the ends of said clamping strips and adapted to be turned to force said hinged clamping strips against the base strip.

2. A trousers creaser having two opposed longitudinally extending base strips, an adjusting bar connecting said strips at their upper and lower ends, a clamping strip hinged on its middle portion to each of said base strips but shorter than the same and adapted to fold over upon said base strip, 40 both ends of said clamping strips being laterally and longitudinally beveled on their outer faces, and angular clamping buttons pivoted on the upper and lower ends of each of said base strips above and below the ends 45 of said clamping strips, the projecting ends of said buttons being beveled and adapted to be turned to force said clamping strips against the said base strips.

In testimony whereof I have signed my name to this specification in the presence of two subscribing witnesses.

CLEMENT D. FAHL.
